CLAIM

I claim the ornamental design for a bicycle brake lever, as shown and described.

DESCRIPTION

FIG. 1 is a perspective view of a bicycle brake lever.

FIG. 2 is a front elevation view of the bicycle brake lever.

FIG. 3 is a rear elevation view of the bicycle brake lever.

FIG. 4 is a left side elevation view of the bicycle brake lever.

FIG. 5 is right side elevation view of the bicycle brake lever.

FIG. 6 is a top elevation view of the bicycle brake lever; and,

FIG. 7 is a bottom elevation view of the bicycle brake lever.

Any broken lines in the drawings illustrate portions of the

bicycle brake lever that form no part of the claimed design.
